Inventor
Henry C. Maul,

UNITED STATES PATENT OFFICE.

HENRY C. MAUL, OF DETROIT, MICHIGAN, ASSIGNOR TO THE MICHIGAN STOVE COMPANY, OF DETROIT, MICHIGAN, A CORPORATION OF MICHIGAN.

MULTIPLE BURNER.

1,174,263.

Specification of Letters Patent.

Patented Mar. 7, 1916.

Application filed September 30, 1915. Serial No. 53,381.

To all whom it may concern:

Be it known that I, HENRY C. MAUL, a citizen of the United States of America, residing at Detroit, in the county of Wayne 5 and State of Michigan, have invented certain new and useful Improvements in Multiple Burners, of which the following is a specification, reference being had therein to the accompanying drawings.

- 10 My invention relates to a multiple burner especially designed for a water heater, and among the objects of my invention may be mentioned, first, that of providing a novel gas burner unit wherein a screen is disposed to prevent back fire without retarding the flow of gas; second, burner units 15 that can be easily and compactly assembled to form a multiple burner having a large flame area, and third, a multiple burner 20 which affords a central opening for a controlling valve.

Reference will now be had to the drawing, wherein:

Figure 1 is a plan of burner units grouped 25 or assembled to heat the coil of an instantaneous water heater; Fig. 2 is a side elevation of a burner unit partly broken away and partly in section; Fig. 3 is an enlarged cross sectional view taken on the line III— 30 III of Fig. 1; Fig. 4 is a similar view taken on the line IV—IV of Fig. 1.

Burner units in accordance with my invention each comprises a mixing tube or pipe 1 having the lower end thereof provided with a conventional mixing device 2 by which air and gas commingle to insure proper combustion when ignited. The upper end of the pipe 1 has an expansion chamber 3 slightly flaring in shape with 35 the bottom thereof provided with an annular interior seat 4 at the juncture of said expansion chamber and the pipe 1. The top of the expansion chamber 3 is rounded off or convex to that extent 40 as to shed water and is closed with the exception of a concentric opening 5 having the walls thereof screwthreaded to receive a threaded plug 6. This plug has the outer end thereof provided with a nut 7 adapted 45 to accommodate a wrench, and the inner end of said plug has a sleeve or positioning member 8 adapted to cooperate with the seat 4 in properly positioning a vertically disposed tubular screen or foraminous body 50. The tubular screen 9 is spaced from the

walls of the chamber 3 and is larger in diameter than the bore of the pipe 1, with said screen of sufficient length to allow gas to pass through the same into the chamber 3 without retarding the flow of gas or reducing the pressure of the same. The tubular screen also serves as a filter and it is through the medium of the plug 6 that the screen can be properly installed and cleaned 60 should occasion require.

The large or upper end of the expansion chamber 3 has a burner head 10 radially disposed relative to the longitudinal axis of the chamber 3 and said burner head has side walls 11 tapering away from the expansion chamber 3, to the end of the burner head, which is closed and has the bottom side thereof provided with positioning lugs 12 and lug receiving sockets 13. The burner head 10 is in communication with the chamber 3 and the side walls 11 of said burner head have jets or ports 14. The jets 14 on one side of the burner head are staggered or alternately arranged relative to the jets 14 on the opposite side of the burner head, 70 this being best shown in Fig. 1, where it will be also observed that the jets of adjoining burner heads are staggered or alternately arranged. With the burner units 75 grouped or positioned as shown in Fig. 1, 80 the disposition of the jets insures a large flame area when the gas is ignited, and with the positioning lug 12 of one burner head extending into the lug receiving socket 13 of another burner head, said lugs and 85 sockets constitute means whereby the inner ends of the burner units, when grouped, are 90 correctly positioned and cannot become accidentally displaced.

The gas outlet openings or orifices of the 95 jets 14 are disposed at an acute angle relative to the vertical plane passing through the axis of the burner head, as best shown in Fig. 4, whereby gas will be directed upwardly and outwardly toward the spaces between the jets of an adjoining burner unit. One of the reasons the jets are not vertical 100 is, because all automatic water heaters collect condensation on the coils which drops and would be deposited in the openings and 105 interfere with the combustion, therefore the top of burner units is made like a roof and the jets of flame are protected from drippings, but the flame is directed at an angle 110 to the horizontal plane to impinge against

the coils. By tapering the expansion chamber 3 and the head of each burner unit, gas admitted to the burner unit is equally distributed at the jets 14, and the position of 5 the tubular screen 9 prevents a back fire without retarding the flow of gas.

I am aware that flat screens or foraminous disks have been positioned in gas pipes to prevent a back fire, but such screens or 10 disks do not provide sufficient area for the passage of gas without retarding the flow of the same, therefore a burner equipped with such screens or disks does not have intense 15 flames as provided by my improved multiple burner, which is essential in connection with an instantaneous water heater.

I attach considerable importance to the grouping or assembling of the burner units as I am enabled to place twelve burner units 20 in a space of fifteen inches in diameter, and as each burner unit has nine jets, there are one hundred and eight jets all told providing a flame of such intensity that water can be heated when flowing through the coil of 25 an instantaneous water heater.

The manner of connecting the inner ends of the burner heads insures a central opening of sufficient size to accommodate an automatic gas and water valve such as shown in 30 and forming the subject matter of a companion application filed Sept. 30, 1915, Serial No. 53382, consequently the burner units are compactly assembled relative to the valve and the entire structure can be readily embodied in an instantaneous water heater having 35 a conventional coil subjected to the action of a burner flame. While the burner units have been found very economical in the consumption of fuel gas, where an intense 40 heat is desired, it is to be understood that the burner units may be used under boilers, in stoves either for heating or cooking purposes, and in many other places.

What I claim is:—

45 1. A gas burner unit comprising a pipe,

an expansion chamber at the upper end thereof, a burner head in communication with the upper end of said chamber, a tubular screen at the lower end thereof seated in the bottom of said chamber, and detachable means in the top of said chamber adapted to hold and position the upper end 50 of said screen.

2. A burner unit comprising an expansion chamber, a jetted burner head disposed at 55 right angles to the axis of said chamber, a tubular screen having the lower end thereof seated in the bottom of said chamber, and a detachable plug in the top of said chamber adapted to hold and position the upper end 60 of said screen.

3. In a multiple burner for water heaters, converging burner heads adapted to receive fuel gas at the outer ends thereof and having tapering side walls provided with 65 jets and the jets of one wall staggered relative to the jets of the other wall whereby the assembled burner heads have staggered jets at the confronting walls thereof affording a large flame area. 70

4. A multiple burner for water heaters, comprising pipes, converging burner heads in communication with said pipes and disposed at right angles thereto, said burner heads having tapering side walls provided 75 with jets and the jets of one wall staggered relative to the jets of the other wall whereby the assembled burner heads have staggered jets at the confronting walls thereof affording a large flame area, and means carried by 80 the inner end of each burner head adapted to maintain the inner ends of said burner heads in spaced relation.

In testimony whereof I affix my signature in presence of two witnesses.

HENRY C. MAUL.
